DIAGNOSTIC COMPOSITION

Alfred H. Free, Elkhart, Ind., assignor to Miles Laboratories, Inc., Elkhart, Ind., a corporation of Indiana
No Drawing. Filed Apr. 13, 1954, Ser. No. 422,977
3 Claims. (Cl. 195—103.5)

This invention relates to diagnostic compositions for the detection and estimation of reducing sugars in body fluids.

The invention has for one of its primary objects, the provision of a simple, rapid and convenient method for performing such test with a high degree of simplicity and without the need for extensive equipment, trained personnel and the like.

The determination of glucose in such body fluids as urine for example, is of signal importance not only in the case of diabetic patients who must control their sugar input, but from another point of view is important in those situations where the detection of disease as a public health measure requires the screening of large numbers of people to determine their physical condition.

There are a number of methods of course, which can be used to measure or estimate the amount of reducing agents in body fluids, particularly urine. The more widely used of the conventional methods are based on the use of alkaline copper solutions which are heated with the material being tested to precipitate cuprous oxide.

The old methods have had the disadvantage that their use has required a certain amount of skill and familiarity with the use of measuring equipment, such as pipettes and the like, the use of liquid reagents some of which, especially the alkaline ones were dangerous to handle, and were inconvenient to transport easily.

More recently, a diagnostic tablet described in U.S. Patent No. 2,387,244 to Compton and Trenneer has found wide usage because of its relative simplicity, accuracy, economy, and the fact that the test could be executed by unskilled persons, as compared to the older tests.

However, all of these tests, techniques and procedures mentioned above, have one draw-back in common, namely they all require heat to perform the tests. In the older methods this heat was supplied by the use of a Bunsen burner or by some other extraneous source of heat.

The aforesaid Compton and Trenneer patent eliminated the need for the extraneous source of heat by providing a "built in" heat source in a tablet combined with a glucose-reagent mixture, which was far superior to the older techniques. However, even in the latter improvement, heat was necessary, which meant that a certain degree of care had to be exercised in the compounding and the subsequent handling of the composition to eliminate the possibility of unintentional generation of the heat as by accidental wetting of the composition.

I have now found a novel and highly useful means for determining the presence or absence of glucose in body fluids, including urine, by a technique which is simple, which does not require the use of external, or in fact any, heat source, and which is otherwise free of many of the disadvantages of the prior art compositions and procedures.

My invention, generally speaking, involves the contacting of the body fluid being tested for reducing sugar content, urine for example, with an enzymatic preparation containing glucose-oxidase and catalase and a subsequent measurement, estimation, or determination of the gluconic acid which is produced when glucose or similar reducing agents are present in the urine. My technique, in any one of its numerous embodiments, which will be described in detail hereinafter, is so simple that it can be used as a qualitative, and even quantitative, test, par-

2

ticularly, by any unskilled person who is able only to determine the presence or absence of a color change.

The following examples will serve to document a number of specific embodiments of my invention, and illustrate the flexibility of the invention. I have chosen these embodiments hereinafter described, as illustrative of my invention and it will be apparent that various modifications may be made without departing from the spirit and scope of my invention.

10

Example 1

A diagnostic tablet weighing 5 grains is prepared in accordance with conventional blending and tabletting techniques, so that it contains as one essential ingredient

15 a glucose oxidase-catalase enzyme. Such an enzyme is the product known as "Dee O" or "Dee G" produced and sold by the Takamine Laboratories, of Clifton, New Jersey. The tablet may contain, conveniently, about 5 mg. of the enzyme together with a sufficient amount of lactose, bentonite, simple inorganic salts, borax, starch and similar fillers and excipients used in tabletting operation.

20 Since a certain amount of oxygen is necessary to carry out the reaction involved, an oxygen-supplying material, like strontium peroxide, barium peroxide, sodium pyrophosphate peroxide, sodium perbor silicate, and similar materials may be added. The oxygen needed for the reaction involved might also be supplied by the addition to the tablet of such oxygen-containing compounds as the iodates and related compounds. It is to be understood, 25 of course, that the amount of enzyme used in the tablet is variable, sufficient being present however, so that in use, that there be enough enzyme to catalyze the oxidation of all of the glucose present in the sample of body fluid being analyzed, to gluconic acid. In addition to the above components there is added to the composition, in accordance with one form of my invention, a sufficient amount of an indicator which will effect a color change 30 at a pH below the normal pH of body fluids, and particularly which changes color at a pH of approximately 4.5 or below. Examples of such indicators are, methyl orange, Congo red, or any other indicator which changes color when the pH of the solution drops below 4.5.

35 In use, a drop or a few drops of the body fluid which is being tested, urine for example, is placed upon the above tablet; if glucose is present in the body fluid, the enzyme will catalyze the oxidation of the glucose to gluconic acid, and a color change on the surface of the tablet indicates the positive presence of glucose in the fluid.

40 It is desirable to include, as one of the components of such a tablet, a small amount of an effervescent couple to facilitate the contacting of the liquid with the solid materials making up the tablet. Under some circumstances it may be desirable to include a surface-active agent to facilitate the wetting of the tablet by the fluid.

45 It is also possible if desired, to omit the aforesaid type of indicator from the composition of the tablet and to perform the test by placing an indicator-free tablet on a test paper which has been treated to change color at a pH of about 4.5 or below, add a few drops of the body fluid being tested to the tablet and observe the color reaction if any, in the area which is wetted by the fluid around the periphery of the tablet.

Example 2

50 A 5 grain tablet made up so that it contains, preferably, about 5 or 10 mg. of glucose-oxidase enzyme such as described in Example 1, together with a sufficient amount of a oxygen supplying compound, such as strontium peroxide to provide all of the oxygen necessary to 55 oxidize the glucose content contained in one cc. of urine, the remainder of the tablet being composed of diluents

such as starch, lactose, borates, such as sodium borate, or other white or preferably colorless compounds. Sufficient effervescent couple may be added so that the tablet readily disintegrates when it is dropped into the urine. The effervescent couple can of course be present in varying amounts, and may comprise from $\frac{1}{10}$ of 1%, based on the weight of the tablet to as much as 50% or even higher; in any event, only sufficient effervescent couple is used, or need be used to assist in the dissolution of the tablet.

Besides using a pH indicator in the tablet, or in a test paper, it is of course possible to use as an indicator, compounds which form color salts or addition complexes of one kind or another with the gluconic acid devolved. Since gluconic acid has well known chelating properties, colored salts of those metals which form chelates with gluconic acid can be incorporated in the tablet or in a test paper used with the tablet to indicate the concentration of gluconic acid obtained when the aforesaid enzyme component of the tablet has a chance to exercise its effect, in the presence of oxygen, on the glucose present in the urine or other body fluid being tested. Examples of such metal salts would be the colored salts of such metals as iron, copper, nickel, calcium, barium, magnesium and the like.

Another variant of my invention is to use a bibulous mat of paper, asbestos or the like, such as is described for example, in the copending application of Alfred H. Free and Helen Free, Serial No. 178,344, filed August 8, 1950, now abandoned. Such a mat is soaked in a solution of a glucose oxidase-catalase enzyme such as hereinbefore described, dried, and the test performed by applying a drop or two of the urine or other body fluid being tested to the mat in the presence of oxygen or an oxygen supplying compound, as well as an indicator to indicate the presence or absence of gluconic acid which is formed.

Since certain changes in carrying out the above techniques, and certain modifications in the compositions which embody the invention may be made without departing from its scope, it is intended that all matter contained in the above description shall be interpreted as illustrative and not in a limiting sense. It is also to be understood that the following claims are intended to cover all of the generic and specific features of the invention herein described, and all statements of the scope of the invention which, is a matter of language, might be said to fall therebetween.

I claim:

1. A method for detecting the presence of glucose in

urine which comprises contacting the urine which is to be tested with a bibulous material which has been impregnated with a glucose-free composition comprising glucose-oxidase and an indicator material which undergoes a color change induced by a reaction product formed when said enzyme is contacted with glucose in the presence of oxygen.

5 2. A test means for detecting glucose in urine which comprises a bibulous material which has been impregnated with a glucose-free composition comprising glucose-oxidase and an indicator material which undergoes a color reaction induced by a reaction product formed when said enzyme is contacted with glucose in the presence of oxygen.

10 3. A test means for detecting glucose in urine which comprises a bibulous material which has been impregnated with a glucose-free composition comprising glucose oxidase, catalase, and an indicator material which undergoes a color reaction induced by a reaction product formed when glucose-oxidase is contacted with glucose in the presence of oxygen.
